IMPROVED WINDOW FASTENER.

WARREN SHAILER, OF DEEP RIVER, CONNECTICUT.

Letters Patent No. 60,267, dated December 4, 1866.

SPECIFICATION.

TO ALL WHOM IT MAY CONCERN:

Be it known that I, WARREN SHAILER, of Deep River, in the county of Middlesex, in the State of Connecticut, have invented a new and improved Window Fastener; and I do hereby declare that the following is a full and exact description thereof, reference being had to the accompanying drawings, and to the letters of reference marked thereon.

The nature of my invention consists in constructing window fasteners with one or both sides diverging from the top, and having a slot to receive a screw for the purpose of attaching them to the sash and allow the wedge form of the side to operate between the screw and casing of the window to hold the window in any desired position; and also having a recess or hook on the lower part, on one or both sides, to receive a screw-head or any suitable catch attached to the casing of the window, and fasten the window when closed.

To enable others to make and use my invention, I will proceed to describe its construction and operation.

I construct my window fasteners to operate on one or both sides of a window, casting them with any suitable metal. A, Figure 1, represents one constructed to operate on the left-hand side of a window, and its operation in fastening the window when raised. S represents a slot by which it is attached to the sash by a screw, on which it easily moves up and down. C represents a recess to receive a screw-head or catch, secured to the casing of a window, and fasten the window when closed.

The mode of attaching, and its operation when attached, are as follows: The diverging or wedge side is placed against the casing and a screw entered a little above the middle of the slot, securing it to the sash. By placing the finger or thumb against the bottom of the fastener and lowering the window, it is held at any desired height by the wedge-shaped side operating between the casing and the screw. Raising the window frees it from the fastening, the screw slipping up in the slot, causing the fastener to drop till the top rests upon the screw, in which position it does not interfere with the movement of the window until it is closed. The window is fastened when closed by marking the position of the recess C on the casing and inserting there a screw opposite the recess, allowing the head to project equal to the depth of the recess. The bottom of the fastener being rounded, it is moved outwardly on coming in contact with the screw in the casing when the window is being lowered, but swings back against the casing when it is closed, the screw-head entering the recess. This position is represented by Figure 2.

Figure 3 is a detached representation.

Figure 4 represents it constructed to operate on the right or left-hand side of a window.

Figure 5 represents it with the wedge side made wide and the top of the slot curved towards it, to adapt it to windows having considerable lateral movement, and also a projection or handle marked e, by which to operate it.

What I claim as my invention, and desire to secure by Letters Patent, is—

The window fastener, substantially as herein described, and represented by figs. 3, 4, and 5.

WARREN SHAILER.
